UNITED STATES PATENT OFFICE

MAURICE C. PIERCE, OF MADISON, WISCONSIN

AUTOMATIC COLLAPSING WHEEL ELEVATING DEVICE

Application filed June 21, 1927. Serial No. 200,386.

My invention relates to new and improved devices for the combined purposes of automatically receiving, elevating, advancing, transferring, holding and lowering of weight bearing wheels, such devices possessing utilitarian and labor and time saving qualities.

It is apparent that, until the present time, the only dependable and universally adopted device for lifting the wheels of heavy vehicles while on the road, is the lifting jack. I am aware that certain other devices involving levers, eccentrics, inclined planes, etc., have been invented and may be in operation in garages and under certain given conditions, but such devices are either too large and heavy to be conveniently stored in a small space in automobiles or they are not universally successful under all conditions and circumstances.

As regards lifting jacks, it would be difficult to describe in detail all of the disadvantages and disagreeable annoyances accompanying their operation. Among various objections the following may, however, be mentioned. The jack is usually dirty and greasy and soils the hands and clothing. It necessitates hard and time-wasting labor under the most awkward circumstances, particularly in connection with elevating the backwheels of automobiles and motor trucks, since gasoline tanks, springs, fenders, etc., prevent easy access to the back axle. The jack must, furthermore, usually be held with one or both hands for proper placement and upright position until its operation has continued sufficiently to wedge it firmly between the axle and the ground. This is especially the case when working on rough or hilly surfaces, on sandy, muddy, or snow covered earth, or on soft ground, since the base of the jack has a tendency to throw the device off the perpendicular and to press unevenly into the earth.

In a majority of cases the jack operator must either kneel, crawl or lie flat on the ground in order to approach his work and this is ruinous to fine clothing, especially when the ground is wet, muddy, or dusty or when working in garages having oily or otherwise dirty floors. Even when overalls or

other suitable working clothes are at hand, the changing into and from them causes an additional loss of time and is particularly impracticable for women operators.

Tender hands become sore and blistered and gloves, if used, are instantly ruined.

In rainy, snowy, or excessively hot or freezing weather the inconvenience of the jack operator is greatly increased through drenching from rain or perspiration or through suffering from frozen hands.

Still another difficulty, resulting in increased loss of time, has been added by the almost universal adoption of balloon tires which require a much greater wheel elevation than formerly was the case with the smaller ones.

Also, in the use of oversized "doughnut" tires, such as are coming into extensive use on airplanes, with the probability of being widely adapted to motor vehicles, with the collapse of the tire, the axle will practically lower on the supporting ground surface so as to preclude the use of an ordinary jack. Obviously, my invention will find particularly valuable applications for use in connection with motor vehicles equipped with tires of this character.

The object of my invention is to obviate the above and other disadvantages and inconveniences and to save time and manual labor through providing a device which will be simple in construction and operation, sure and reliable under all conditions, small in size, light in weight, clean to handle, compact, inexpensive, durable, and in fact, with all a practical every day device which will elevate, hold in elevation, and lower at will only, the wheels of vehicles through the utilization of the vehicle's own motive power; this to be accomplished in such a manner that, when a suitable support or rest is placed between the axle and the ground, the wheel or wheels will remain freely suspended well above the ground for removal, repairs, or release from weight bearing. The device will further provide for elevating a collapsed vehicle tire if the axle is lowered to a point only a few inches above the supporting ground surface, precluding the use of an ordinary jack.

With these and other objects in view which may be incident to my improvements, the invention consists in the parts and combinations to be hereinafter set forth and claimed, 5 with the understanding that the several necessary elements comprising my invention may be varied in construction, proportions and arrangement, without departing from the spirit and scope of the appended claims.

10 In order to make my invention more clearly understood, I have shown in the accompanying drawing means for carrying the same into practical effect, without limiting the improvements in their useful applications to 15 the particular constructions which, for the purpose of explanation, have been made the subject of illustration.

In the drawing, Figure 1 is a side view of 20 my novel automatic collapsing wheel elevating device, shown in the operative position;

Figure 2 is a top view of the device;

Figure 3 is a sectional view, taken along the line 3—3 of Figure 1;

Figure 4 is a sectional view, taken along 25 line 4—4 of Figure 1; and

Figure 5 is a side view of the device, shown collapsed.

Similar numerals refer to similar parts throughout the several views.

30 The inclined plane member 1, is shown as composed of a section of channeled steel with notches 2, milled into the flanges on its upper surface and cut at its upper or elevated end to permit the flanges on its upper surface 35 to extend, these extensions 3, making possible the pivotal connection 4. The inclined plane member 1, is cut on the diagonal at its bottom end 5, and has inserted between its upper surface flanges a strip of suitable non-skid- 40 ding material 6, which is allowed to extend for a short distance away from the base of the plane to form a friction apron approaching apron to the plane.

An approaching friction apron base 7, hav- 45 ing vacuum cup rubber or other suitable non-skid material attached to its bottom 8, is connected to the under side of the plane through a pivotal attachment 9.

The elevated track member 10, is likewise 50 composed of a section of channeled steel, although somewhat wider than that which com- 55 poses the inclined plane, and its end which connects with the plane is similarly cut to provide rounded extensions 11, to connect with the pivot 4. The opposite or free ex- 60 tremity of the elevated track member is bent upward to form a bumper or stopper 12. The stop 12 acts as an indicator to advise an operator that the wheel of the vehicle is ele- 65 vated on the device to such a distance that further movement of the vehicle may be controlled and discontinued at any desired point.

A combined support for both the plane and the elevated track is provided by means of a 65 forwardly inclined pivotal leg 13, with an

extended and wide chisel edged base 14. The vacuum cupped rubber, or other suitable known non-skidding material adapted to the bottom 8 of the apron base 7, and the chisel edged base 14 on the pivotal leg 13, provide for a desirable slow collapsing of the device when the tension member 23 (to be later described) is released. The top end of this support is cut in a suitable angular manner 70 75 15, and is attached with a pivot bolt 16, to the elevated track member at or near the latter's point of connection with the plane.

The provision of this middle support is necessary for the elevating of very heavy vehicles, such as automobile busses and trucks, 80 but might be eliminated when the device is designed specially for light passenger cars without materially altering my invention. The pivotal arrangement connecting the plane and the track would in the latter event 85 be slightly altered for increased strength.

To the under side of the elevated track member and at or near its free upturned extremity is attached a second forwardly inclined support 17, having a wide, extended and chisel edged base 18, its upper extremity being cut at a suitable angle and pivotally connected by means of a swing bolt 19. The supports 13 and 17, together with the transverse extension of the thin wide chisel edged 90 95 bases 14 and 18, insure the device against longitudinal movement and toppling laterally when the vehicle wheel is supported thereon.

A tension or spacer member 20, is provided and connects pivotally with the two supporting legs at or near their respective bases by means of swing bolts 21, and 22. The elimination of the middle support would obviate the necessity for this tension member.

A second tension or spacer member 23, is 105 110 115 120 125 130 135 140 145 150 155 160 165 170 175 180 185 190 195 200 205 210 215 220 225 230 235 240 245 250 255 260 265 270 275 280 285 290 295 300 mediately fall flat on the ground. This falling flat on the ground is fortunate in that it assists in and nearly accomplishes the complete collapsing, so desirable for compact storage purposes.

All that is required to completely fold the device for storage is to pivot the inclined plane member upward until it swings down on to a resting position on the top of the runway member. It is, then, in this compact and space economizing form that my device will be found when wanted for use.

The extremely simple operation of my device may be described as follows:

Presuming that an automobile while on the road or in the garage is observed to require a change of wheel or that one or more of the wheels must be lifted free from the ground for any other reason; my device will then be removed from its storage space within the car. It will instantly be made ready by swinging the inclined plane member downward and slipping the aperture near the free extremity of the tension member on to the projecting bolt pin near the base of middle support 13.

The device, being now ready for operation, is next placed close to and absolutely straight in the path of the wheel to be lifted, the upper surface of the inclined plane member obviously facing the wheel. The car is then driven slowly forward until the wheel has mounted the inclined plane and has come to rest on the upper surface of the elevated track. The wheel has thus been lifted in an instant and without physical effort.

At this point it may be desirable to set the emergency brake of the car.

In order to absolutely insure the success of the above mentioned elevation operation, it is well to observe the following slight precautions:

First, the front wheels should point straight forward in exact line with the body of the automobile.

Second, my device, as previously stated, should be placed exactly straight in the path of the wheel to be lifted.

Third, the car should be driven preferably slowly forward and in an exact straight line.

Fourth, brakes should be applied as soon as the wheel has rolled past the apex of the inclined plane.

The overwhelming advantages of this type of elevating as compared with the employment of lifting jacks will be realized as a result of the foregoing description, but the realization becomes all the more striking when one reflects upon the enormous weights to be lifted when elevating wheels of loaded busses, trucks, etc.

In as much as the ultimate object of the above described operation is to leave the elevated wheel freely suspended above the ground, it is apparent that an auxiliary hold-

er or support on to which the lifted weight is transferred must accompany my device. Such holder must obviously be placed in supporting position between the ground and some substantial part of the vehicle near the lifted wheel.

It is not my intention at this time to recommend or prescribe any particular kind of support, automatic or otherwise, with which to hold the axle in abnormal elevation. It may be essential and at the same time sufficient that I point out the existence of sufficient supports for this purpose. In as much as the lifting jack is adjustable and designed to bear heavy weights, it may, for instance, be used as a holder after the work of lifting has been performed by the car with the aid of my device.

Assuming then that a jack, or other support, has been placed under the elevated end of the axle and has been adjusted to proper height, there is only one slight action required to complete the suspending operation. This action consists in grasping the handle at the free end of the chain attached to the tension member 23 engaging extremity and imparting an outward jerk to the latter. A slight outward blow imparted to the knob will also accomplish the same purpose. The immediate result is that the free end of the tension member slips off from the projecting bolt pin and the device falls to the ground leaving the elevated wheel freely suspended in the air.

After a change of wheel or tire or necessary repairs have been completed, the lowering to the ground of the suspended wheel is in order. This may be simply and instantly accomplished in one of many ways, all without physical effort. Setting aside, however, all other possibilities the following description will explain how my invention may be used as a lowering device as well as in the capacity of an elevator through approximately the same manner of employment.

It will again be set in operating position in the path of the elevated wheel, but this time on the opposite or reverse side thereof and wedged tightly between the latter and the ground. The car is then driven slowly in the opposite direction from that of the first operation until the raised wheel comes once more to rest on the elevated platform of the device. From this position the wheel may be allowed to roll gently down the inclined plane and back onto the ground.

My device, as a whole and much of its construction and parts, possess novelty as far as I am aware, yet my experiments and tests have been made principally with a view to obtaining serviceability and reliability under all conditions. The following features are emphasized because they are believed to possess outstanding unique utility.

The position and outward diagonal slant of

the supporting legs have given the best results for strength and bracing against the weight of an automobile wheel as the latter mounts the inclined plane.

5 The position and outward diagonal slant of the second leg support at the free end of the elevated track has been found to be the best guard against the possible toppling over forward of the device when the advancing wheel bumps against the upturned stopper.

10 The forwardly inclined slant of the supporting legs holds their non-skid bases in the best position for securely gripping loose and insecure ground surfaces.

15 The diagonal cut of the upper or connecting end of the second leg together with the position of its pivot affords a most suitable rest for the track, and offers a most effective resistance against swinging backward when

20 under pressure of an advancing wheel, yet permits easy forward pivoting when desired.

The double angular cut of the upper or connecting end of the middle leg 13 together with the position of its pivot presents a most suitable rest for the connecting extremities of both the inclined plane and the elevated track, assists in holding the leg in its intended angle position without fear of back swing when under pressure of an advancing wheel, and gives support to both elevated members when subjected to the heaviest weights, yet permits easy forward pivoting when desired for collapsing.

30 The results obtained with tension holding members have justified their employment in preference to other kinds, quite aside from the principle that any member subjected to pull may be very light in proportion to its holding capacity. As employed with my de-

40 vice, they, very fortunately, hold the various bases firmly in position and assist most efficiently in forming a solidly braced frame capable of receiving and supporting the heaviest weights.

45 Another fortunate and perhaps novel feature is the locking device which is not only strong, reliable, quick, and simple in operation, but absolutely necessitates that the hand of the operator be well clear of the device when the latter falls to the ground. This is highly desirable and comes as a result of the outwardly directed jerk or blow imparted to the fastening member at its locking extremity.

50 It is apparent that the successful operation of my device is much dependent on its non-skidding and non-slipping features, namely, the friction surface of the inclined plane and the three different ground grips applied to its bases, and in addition thereto the approaching friction apron. Experiments have shown me the necessity of combining ground grips of these sorts as an absolute guarantee against circumstances of hard and soft, semi-hard and semi-soft sur-

faces and as against rough and smooth surfaces as for instance, concrete, asphalt, brick, sand, mud, snow, ice, wood, macadam, dirt, stones, rocks, sod, hills, holes, ruts, slopes, etc., and in addition thereto it was found necessary to consider the effects of water and oil on all surfaces.

55 A knowledge of lifting jacks together with my experiments with the device above described have shown the necessity for large surfaced bases to accompany lifting devices which may be used on soft ground as a prevention against their sinking into the earth. My device has therefore been provided with bases of ample bearing surface, arranged and distributed in the most efficient manner from the standpoint of required balance and easy manipulation when in operation and space economy when folded away for storage.

60 First of all, my experiments showed that an inclined plane of any appreciable angle of ascent would slip away from an advancing wheel on certain surfaces before even the slightest weight had been transferred onto its upper surface. The plane bumped away from the wheel, so to speak. To prevent this occurrence, I supplied the plane with its approaching apron which extends out onto the ground so flatly that no wheel will refuse to roll onto it. The weight of the wheel having been actually transferred to an attached part of the plane, the result is that the plane is caught, as it were, and held in position until the weight is actually pressed, in turn, downward on the upper surface of the plane itself. 100 This was found sufficient under ordinary circumstances to hold the plane fast to the road as the operation continued.

65 Experiments on slippery concrete and asphalt soon proved however, that a plane of any appreciable ascent would refuse entirely to accept an advancing wheel no matter how slowly it was rolled forward. This necessitated the adoption of the vacuum cup bottom to the base of the plane as the most certain means of preventing skidding on smooth, hard surfaces.

70 Experiments on soft dirt, sand, snow, ice, etc., showed the necessity for still another kind of ground surface grip and consequently the broad extending chisel edged bases were added to the leg supports. These bases cut and plow into soft and semi-soft surfaces and prevent the forward sliding of the device, their side extensions prevent the same from falling or sinking over sideways and their large bearing surfaces prevent them from being pressed into the earth.

75 The upturned bumper at the free extremity of the elevated track serves a valuable purpose and may have a claim to novelty in a device of exactly this kind, although I recognize in it a very old method of stopping an advancing wheel.

Having thus described my invention, I claim:

1. In a device for the purpose set forth, two channeled members having their ends pivotally connected, one designed to be arranged horizontally and the other at an angle, the lower end of the angle member being cut diagonally and having pivotally secured thereto and extending therebeyond a base plate, a friction surface on the under face of the base plate, a support pivoted to the under face of the horizontal member and having its ends cut angularly to underlie both the horizontal and the angle members and having its lower end widened and formed with a sharpened extension, a second angularly disposed support pivoted beneath the outer end of the horizontal member and having its outer end widened and sharpened and removable tension bars between the supports and the angle channel member, for the purpose set forth.

2. A foldable and collapsible device for the purpose set forth, comprising a channeled member designed to provide a track or runway and having one end rounded to form a stop, a second channeled member designed to be arranged at a downward inclination from the first mentioned member and being pivoted to the straight end thereof, said second channeled member having a friction strip fixed on its inner face and extending from the outer end thereof, and its said outer end cut diagonally, a base pivotally secured to and supporting the outer end of the said second channel member and projecting therebeyond and receiving the friction strip thereof, said base having its under face provided with a friction surface, a forwardly inclined intermediate support pivoted to the flanges of the first mentioned channeled member and having its end cut at opposite angles to underlie this member and the second channeled member, said support having its lower end widened and formed with a sharpened tooth, a second forwardly inclined outer support pivotally secured between the flanges of the runway and contacting with the base thereof, said outer support having its lower end widened and toothed, a tension brace removably pivoted to the supports, a second notched member pivotally secured to the inclined channel member, a headed pin on the intermediate support to receive the notch of said member therein and a pull chain on the free end of the said member.

3. A device for elevating a wheel on movement thereof comprising means to raise a wheel to an elevated horizontal plane, means connected to one end of the raising means to facilitate mounting of the wheel thereon, means associated with the same end to prevent longitudinal movement, and means associated with the raising means to maintain the wheel elevated.

4. A device for elevating a wheel on move-

ment thereof comprising means to raise a wheel to an elevated horizontal plane, means connected to one end of the raising means to facilitate mounting of the wheel thereon, means associated with the same end to prevent longitudinal movement, means to limit further movement of the wheel on the elevated horizontal plane, and means associated with the raising means to maintain the wheel elevated.

5. A device for elevating a wheel on movement thereof, comprising means to raise a wheel to an elevated horizontal plane, means connected to the raising means to facilitate mounting of the wheel thereon, means to prevent longitudinal movement, means associated with the raising means to maintain the wheel elevated, and means on the raising means to indicate the elevation of the vehicle thereon.

6. A device for elevating a wheel on movement thereof, comprising means to raise a wheel to an elevated horizontal plane, means connected to the raising means to facilitate mounting the wheel thereon, means to prevent longitudinal movement, means associated with the raising means to maintain the wheel elevated, means to collapse the device with the wheel elevated thereon, and means associated with the device to retard collapsing thereof.

7. A device for elevating a wheel on movement thereof, comprising means to raise a wheel to an elevated horizontal plane, means connected to the raising means to facilitate mounting of the wheel thereon, means to prevent longitudinal movement, and means associated with the raising means to maintain the wheel elevated, the wheel elevating means being mounted against lateral tipping or toppling movement.

In testimony whereof I affix my signature.
MAURICE C. PIERCE.
